RIVET

Austin Gudmundsen, Milwaukee, Wis., assignor
to Gudmundsen Stratton Laboratories, Inc.,
Milwaukee, Wis., a corporation of Wisconsin

Application January 26, 1942, Serial No. 428,175

1 Claim. (Cl. 85—40)

This invention relates to rivets and riveting.

In many instances, where riveting is employed, as in metal airplane construction and in small sized tanks, space is not available for the "dolly" or anvil to be properly held against the head of the rivet while the rivet is being upset or headed.

It is, therefore, an object of the present invention to provide a novel rivet and method of setting the same which obviates the need for holding an anvil against the head of the rivet during the riveting operation and instead permits the setting operation to be completed entirely from in front of the work.

With the above and other objects in view which will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claim.

The accompanying drawing illustrates several complete examples of the physical embodiments of the invention constructed according to the best modes so far devised for the practical application of the principles thereof, and in which:

Figure 1 is a sectional view illustrating the rivet of this invention and the tool used for setting the same, with the rivet about to be set;

Figure 2 is a view similar to Figure 1 but showing the rivet set or formed;

Figure 3 is a view of the completed connection;

Figures 4 and 5 are views similar to Figure 3 illustrating slightly modified embodiments of the invention; and

Figure 6 is a perspective view of the rivet per se.

Referring now particularly to the accompanying drawing, in which like numerals indicate like parts, the numeral 5 designates generally a rivet constructed in accordance with this invention. The rivet is formed of suitably ductile metal and comprises a shank 6 with a head 7 at one end thereof.

Extending down through the head and into the shank is a well 8, the closed bottom of which is in the end of the shank remote from the head. The mouth of the well is taperingly enlarged as at 9 to provide a socket for the reception of a pressure gun tip 10. A thin-edged lip 11 bounds the mouth of the well to effect a better seal with the gun tip.

In use, the rivet is inserted through the aligned holes in the two parts or plates 12 to be secured together with the head bearing against one of said parts and the shank protruding beyond the other.

The tip of the fluid pressure gun is then applied

to the socket 9 which forms the mouth of the well and a "shot" of fluid pressure from any suitable source is injected into the well. This fluid pressure which may be hydraulic or pneumatic, expands the end of the shank to a substantially bulbous shape as shown in Figure 2 thereby clamping the plates or parts 12 between the expanded portion and the head.

After being set or formed in this manner, the lip 11 is burnished or otherwise swedged over to provide a substantially smooth outer surface as shown in Figure 3. Burnishing over the lip 11 closes the mouth of the hole or well as will be readily apparent.

In instances where added strength is necessary, a shear reinforcing pin 13 may be driven into the well before the lip 11 is burnished over as illustrated in Figure 4.

The invention is, of course, adaptable to flush type or flat headed rivets shown in Figure 5 as well as it is to the round headed rivets shown in Figures 1 to 4 and 6.

From the foregoing description taken in connection with the accompanying drawing, it will be readily apparent to those skilled in the art that this invention provides a novel rivet and method of riveting by which the difficulties attending conventional riveting and resulting from cramped space conditions are eliminated and riveting from one side of the work is made possible.

Attention is also directed to the fact that the pressure employed in holding the fluid pressure gun against the rivet serves to firmly hold the rivet in place with its head snugly against the adjacent surface of the work during the setting of the rivet.

What I claim as my invention is:

A rivet comprising: a shank of ductile metal enlarged at one end to provide a head; a well closed at the bottom extending down into the shank from the head end of the rivet, said well being taperingly enlarged outwardly from a point in the head adjacent to but spaced a distance 40 from the junction between the head and shank so as not to weaken the shank; and an upstanding annular lip on the head encircling the mouth of the well and through which said taperingly enlarged portion of the well leads, the tapering 45 wall portions of the lip and head providing a tapered seat of substantial axial length sufficient for good sealing engagement with the tapered tip of a shank expanding tool inserted into the taperingly enlarged mouth of the well, and said 50 lip being adapted to be bent inwardly to close the mouth of the well and form a continuation of the top surface of the head.

AUSTIN GUDMUNDSEN.
